UNITED STATES PATENT OFFICE

MARCUS ASH MYERS, OF GLOVERSVILLE, NEW YORK, ASSIGNOR TO MYERS' WOOLLY ANIMALS, INC., A CORPORATION OF NEW YORK

DESIGN FOR A CARRYING BAG

Application filed February 15, 1928. Serial No. 25,452. Term of patent 3½ years.

To all whom it may concern:

Be it known that I, MARCUS ASH MYERS, a citizen of the United States of America, residing in Gloversville, county of Fulton, and State of New York, have invented a new, original, and ornamental Design for a Carrying Bag, of which the following is a specification, reference being had to the accompanying drawings, forming a part thereof.

Fig. 1 is a side view of a carrying bag illustrating my new design.

Fig. 2 is an end view showing the flaps, upon either side of the opening in the bag, spread apart.

I claim:

The ornamental design for a carrying bag, substantially as shown and described.

This specification signed this 15th day of January, 1928.

MARCUS ASH MYERS.
